UNITED STATES PATENT OFFICE.

GEORGE E. HENRY AND CHARLES F. HENRY, OF PHILADELPHIA, PENNSYLVANIA.

NON-REFILLABLE BOTTLE.

SPECIFICATION forming part of Letters Patent No. 605,227, dated June 7, 1898.

Application filed August 31, 1897. Serial No. 650,100. (No model.)

To all whom it may concern:

Be it known that we, GEORGE E. HENRY and CHARLES F. HENRY, citizens of the United States, residing at Philadelphia, in the county 5 of Philadelphia and State of Pennsylvania, have invented a certain new and useful Improvement in Non-Refillable Bottles, of which the following is a specification.

Our invention relates to a new and useful 10 improvement in non-refillable bottles, and has for its object to provide a simple, cheap, and effective device of this description, which having once been filled and sealed the contents thereof cannot be withdrawn without giving 15 a positive evidence of the same.

It is a well-known fact that the goods of certain manufacturers are imitated by others using the bottles in which the original goods were sold after the contents have been withdrawn therefrom and refilling the same, and thereby deceiving the public into buying an inferior article, as well as defrauding the original manufacturer of his just returns, and also injuring his reputation; but by the use of our 25 improvement this is entirely overcome, since a bottle cannot have its contents withdrawn therefrom and be then refilled and sealed as the original package without detection by the most casual observer, since the seal or detector will, when the bottle is once opened, drop therein, where it will remain as evidence of the fact that the bottle has been opened.

In order that those skilled in the art to which this invention appertains may understand 35 how to make and use the same, the construction and operation will now be described in detail, referring to the accompanying drawings, forming a part of this specification, in which—

40 Figure 1 is a section of the upper portion of a bottle, showing a portion of our improvement applied thereto, while the stopper and its attachment are shown in a position to be forced within the mouth of the bottle; Fig. 45 2, a similar view showing the stopper forced within the mouth of the bottle and in engagement with the keeper; Fig. 3, a similar view showing the cork and keeper withdrawn, with the consequent result of the detector being 50 precipitated within the bottle; Fig. 4, a detail perspective of the protector carried by

the stopper; Fig. 5, a similar view of the keeper; Fig. 6, a slightly-modified form of our improvement, in which the protector is dispensed with and the snap-hooks secured 55 directly to the stopper; Fig. 7, an elevation of this construction, looking at right angles to Fig. 6; and Fig. 8, a detail of the strap and hooks which are secured to the stopper.

In carrying out our invention as embodied 60 in Figs. 1 to 5, inclusive, 1 represents the neck of a bottle, in which a circuitous passage-way 2 is formed by suitable projections, while the mouth 3 thereof is somewhat enlarged, as clearly shown. A keeper 4, which 65 may be of glass, porcelain, or other suitable material, is adapted to fit within the mouth and rest upon the shoulders 5, and this keeper has attached thereto in any suitable manner a wire 6 of square cross-section by means of 70 two branches thereof, the main strand of which extends downward through the circuitous passage within the neck and has attached to its lower end a detector-ball 7, which may be of any desired material. The ball 75 and the keeper after being secured together by the wire 6 are suitably supported within the mold and the bottle formed therearound.

Vertical slots 8 are formed within the periphery of the keeper diametrically opposite 80 each other and have secured thereacross the wires 9, which in practice may be molded within the keeper, for the purpose hereinafter set forth. This keeper has a central opening 10 of sufficient size to permit the free inflowing of the liquid when the bottle is being 85 filled and is held in place so long as the detector 7 remains suspended upon the wire 6.

11 represents the protector, which is preferably made of some refractory material 90 which cannot be easily controlled, so that when it is in place within the mouth of the bottle it will prevent tampering with the keeper, and this protector has slots 12 formed in its periphery diametrically opposite each 95 other, and secured therein are the snap-hooks 13, which are here shown as made of a single piece of spring metal extending across the top of the keeper and downward through the slots, and finally terminating in the hooked 100 ends 14. A hole 15 is formed through the keeper and metal strip for the passage of the

rod 16, which also passes through the stopper 17 and has run upon its lower end a nut 18, whereby both the stopper and protector are secured together, while the upper end of this 5 rod has formed therewith or secured thereto a cap 19, which covers the stopper and prevents the rod from being drawn therethrough. This cap may have a ring 20 attached thereto, whereby the drawing of the stopper may 10 be facilitated.

When the stopper is forced in place, the protector passes downward, and the hooks carried thereby, when brought in alinement with the slots 8, will engage with the cross-wires 9 and snap under the same, so that the stopper and its protector cannot be again withdrawn without also drawing upward the keeper, and as this would be impossible without breaking the wire 6 it follows that in so 15 20 doing the detector 7 will be precipitated within the bottle.

From this description it will be seen that when the bottle is properly supplied with our improved keeper and detector it may be filled 25 prior to being corked in same manner as the filling of any other bottle is accomplished, but after it has once been filled and the stopper forced in place, so that the hooks 13 engage with the cross-wires of the keeper, as 30 just described, it cannot be opened and its contents withdrawn and refilled without detection by the most casual observer, since the ball 7 will then remain in the bottom of the bottle and move about therein when the 35 bottle is used. The same result may be accomplished by the construction in Figs. 6, 7, and 8, in which 21 represents the stopper, around which is secured a metal band 22, having formed therewith the snap-hooks 23, and 40 these hooks are adapted to enter into engagement with the cross-wires of the keeper, as before set forth and for the same purpose, so that when this construction is used a protector is not necessary.

45 Other slight modifications may be made in the construction here shown and described without departing from the spirit of our invention, and we do not wish to be limited to these exact details.

50 Having thus fully described our invention, what we claim as new and useful is—

1. In combination with a bottle, a keeper

secured in the mouth thereof, said keeper having grooves formed in its sides, wires extending across said grooves, a detector secured to the keeper whereby when said keeper is withdrawn the detector will indicate the fact, a stopper carrying catches adapted to engage the cross-wires of the keeper, as and for the purpose described. 60

2. In combination, a bottle having a neck in which a circuitous passage is formed, a mouth of larger interior diameter, a keeper located within the mouth and resting upon shoulders, a wire, a detector suspended from the keeper by said wire, a protector adapted to fit upon the keeper, means for attaching said protector to the keeper, and a stopper to which the protector is secured, substantially as shown and described. 65 70

3. In combination with a bottle of the character described, a keeper adapted to fit within the mouth thereof and rest upon suitable shoulders, said keeper having grooves formed in its sides, cross-wires extending across said 75 grooves, a protector adapted to fit upon the keeper, catch-hooks carried by said protector for engagement with the cross-wires, a stopper secured to the protector, a wire suspended from the keeper, and a detector secured to the lower end of this wire, substantially as and for the purpose set forth. 80

4. In combination with a bottle, a keeper secured in the mouth thereof, said keeper having grooves formed in its sides, wires extending across said grooves, a detector secured to the keeper whereby when said keeper is withdrawn the detector will indicate the fact, a protector, a cork secured on said protector, and catches formed of a single piece of sheet 90 metal, said piece of metal being secured between the cork and protector, the ends thereof being bent downwardly and hooked to engage the cross-wires of the keeper, substantially as set forth. 95

In testimony whereof we have hereunto affixed our signatures in the presence of two subscribing witnesses.

GEORGE E. HENRY.
CHARLES F. HENRY.
